UNITED STATES PATENT OFFICE.

LESLIE DANA, OF BRENTMORE PARK, MISSOURI, ASSIGNOR TO CHARTER OAK STOVE & RANGE COMPANY, A CORPORATION OF MISSOURI.

DESIGN FOR A STOVE.

45,835.

Specification for Design.

Patented May 26, 1914.

Application filed March 14, 1914. Serial No. 824,822. Term of patent 14 years.

To all whom it may concern:

Be it known that I, LESLIE DANA, a citizen of the United States, and resident of Brentmore Park, St. Louis county, State of Missouri, have invented a new, original, and ornamental Design for Stoves, of which the following is a specification, reference being had to the accompanying drawing, forming part thereof.

The figure shown is a perspective view of a stove, showing my new design.

I claim:

The ornamental design for a stove, as shown.

LESLIE DANA.
